UNITED STATES PATENT OFFICE.

JACOB J. UNBEHEND, OF SYRACUSE, NEW YORK, ASSIGNOR TO JUDSON L. THOMSON & CO., OF SAME PLACE.

RIVETING-MACHINE.

SPECIFICATION forming part of Letters Patent No. 363,923, dated May 31, 1887.

Application filed December 27, 1886. Serial No. 222,632. (No model.)

To all whom it may concern:

Be it known that I, JACOB J. UNBEHEND, of Syracuse, in the county of Onondaga, in the State of New York, have invented new and useful Improvements in Riveting-Machines, of which the following, taken in connection with the accompanying drawings, is a full, clear, and exact description.

My invention relates to improvements in riveting-machines for securing rivets in the heels of arctics and like overshoes, and has for its object the protection of the combined adjustable shoe-holder and riveting-block, upon which the overshoe may be securely held and accurately adjusted to the device for heading the rivets with great rapidity and uniformity; and to this end the invention consists in a machine for securing rivets in the heels of arctics and like overshoes, of the combined adjustable shoe-holder and riveting-block, and of the combination of a pivoted riveting-block having an adjusting mechanism consisting of a vertically-guided screw carrying the riveting-block with the adjustable shoe-holder and plunger for raising the same, and a spiral spring for retracting the riveting-block, and a device for securing the riveting-block in its operative position, all as hereinafter more particularly described, and pointed out in the claims.

It also consists in the detail construction and arrangement of the parts, as hereinafter fully described, and pointed out in the claims.

In specifying my invention reference is had to the accompanying drawings, in which like letters indicate corresponding parts in all the views.

Figure 1 is a side elevation showing the general construction and arrangement of the parts. Fig. 2 is a top plan showing the adjustable shoe-holder and riveting-block in their operative position. Fig. 3 is a longitudinal vertical section taken on line *x* *x*, Fig. 2. Fig. 4 is a transverse section taken on line *y* *y*, Fig. 1. Fig. 5 is an enlarged detached detail of the screw for adjusting the riveting-block, showing the thread and groove for guiding the riveting-block rectilinearly in its vertical adjustment. Fig. 6 shows, respectively, a rear side

and edge view of the spring-stop for holding the adjusting-nut from turning on the screw of the riveting-block; and Fig. 7 is an enlarged detached detail of the riveting-dies which are secured in the riveting-block.

A represents the stock of the adjustable riveting-block and combined adjustable shoe-holder, and the same consists of the cylindrical tubular vertical section *A'* and the angular foot or arm *A*². The stock *A* is pivoted at *F* onto the frame *M* of the machine carrying the rivet-heading mechanism, which machine may be of the character described in my application "A," of even date herewith.

The tubular vertical portion *A'* of the stock *A* has a tongue, *a*, on the interior, as best shown in the transverse sectional view Fig. 4, which, in connection with a suitable groove, *a'*, in the screw *G* of the riveting-block *B*, serves to guide the riveting-block *B* rectilinearly vertically without permitting the screw to turn in its upward movement.

B is the combined riveting-block and adjustable shoe-holder, and it consists of the anvil portion or head *B'* and the screw or shank *G*. The threaded portion of the screw *G* fits down into the tubular portion of the stock *A'*, the tongue *a* of which engages the groove *a'* in the side of *G*, for the purpose already explained.

C is the adjusting-nut, threaded on its interior to engage the thread of the screw *G*, and it serves to raise or lower the riveting-block *B* by turning the same in the usual manner.

The exterior of the adjusting-nut *C* is provided with the groove-shaped serrations *c e*, which extend vertically from top to bottom of the adjusting-nut, for the purpose which will be presently explained.

The head of the riveting block or anvil *B* is provided with apertures *L L* for the reception of dies *l l*, Fig. 7, which fit into the apertures *L L* and serve to spread or clinch the prongs of the rivets in the heading operation when the same are inserted in the arctics or overshoes, as will be presently explained.

Upon the side of the riveting block or anvil *B* is secured a plate, *J*, which supports one end of the spiral spring *K*, the other end of which is secured to the stock *A*, as illustrated

in Fig. 1. The office of the spiral is to retract the anvil or riveting block B when the same is forced up in the operation of heading the rivets.

5 D D' represent the portion of the shoe-holder which supports the toe and sole of the shoe, the heel of which is supported on the riveting-block B, and the shoe-holder is made adjustable by providing the two parts B D' with the slots d d and lapping one over the other, securing the same by means of the clamping-screws E E, Fig. 2.

It will be observed that the supports D D' may be readily adjusted for straining an over-shoe onto the anvil or riveting block B by loosening the clamping-screws E E and adjusting the supports D D' to the length of the shoe, and that the shoe is firmly held on the adjustable shoe-holder and riveting-block when the same is tightly strained thereon in the manner explained.

It will be understood that my invention is to be used in connection with such riveting-machines as belong to the class described in my application "A," above referred to, of even date herewith, in which the combined shoe-holder and riveting-block are located underneath feeding mechanism which feeds the rivets to the block, and thus forces the rivet against the clinching-dies l l, held in the holders L L of the block B, as explained, to head or clinch the rivets, and since the shoe comes in close proximity to the feeding mechanism when brought into position for clinching the rivet, it follows that the combined shoe-holder and block must be so attached to the frame of the machine as to enable the operator to swing it out from the feeding mechanism to have room to readily apply the overshoe to the holder without interfering with the feeding mechanism; hence, the stock A is pivoted to the frame M of the machine in the manner illustrated at F, Figs. 1 and 3.

In order to securely hold the riveting-block and shoe-holder under the feeding mechanism, I provide the spring H, (best shown in Figs. 2 and 3,) consisting of a spring-plate located underneath the frame of the machine, and having a stud, I, extending through an aperture in the frame and taking in a recess, I', in the under side of the stock A. When the stock is swung with the shoe under the feeding mechanism and the punches, the stud I takes in the recess I' in the stock A and securely locks the stock in position for the heading operation, and by simply depressing the handle or thumb-piece H of the spring the stud I is released from its engagement in the recess I' and the riveting-block may be swung out from under the feeding mechanism and punches and the operation repeated.

Upon the side of the stock A, at a point immediately in front thereof, I secure a spring, S, having the end S', through which pass the securing-screws which fasten it to the stock A, and the head s is provided with a curved

extension which takes in the groove-shaped serrations of the adjusting-nut C. The object of the spring S is to form a stop to prevent the adjusting-nut C from turning during the 70 operation of heading the rivets. I

It will be understood that the adjusting-nut C is loosely mounted on top of the tubular portion A' of the stock A, the screw G of the riveting-block B passing through the said nut, 75 and that the office of the nut is solely to adjust the block B vertically to bring the over-shoe to the proper height for receiving the rivets; hence it is desirable to prevent the turning of the block or any deviation thereof, 80 and this desirable result I secure by forming the groove-shaped serrations on the outer surface of the nut, as shown in Fig. 1, and providing the spring S, interlocking therewith by means of the curved projecting head s, which 85 fits closely into the serrations and prevents the nut from turning until sufficient pressure is applied to the nut to release the head-extension s therefrom, when the nut may be turned to regulate the height of the anvil-block at will.

P is the plunger, operated in any suitable manner from underneath the stock to push upward the riveting-block B in the heading operation; and in order to adapt the riveting-block to the stroke of the plunger, or, in other words, to adjust the same accurately for the given length of rivet, I provide the screw B', which takes in the threaded seat p, Fig. 3, which permits the adjustment of the stroke 90 as desired.

The operation of my invention is as follows: A rubber arctic or overshoe is applied onto the combined adjustable shoe-holder and riveting-block in the manner already explained, 105 and the stock is swung around under the rivet-feeding mechanism and locked in position by means of the spring H and the stud I. The rivets are fed down into the heel or sole of the arctic or like overshoes, when the heading operation is performed by pushing up the riveting-block B, which is accomplished by means of the plunger P, which forces up the block, and the dies l l clinch the prongs as the rivet is forced downward through the shoe, and the 115 spiral K retracts the riveting-block B back to its normal position.

The form of the riveting-dies l l may be varied at will, and die-plates may be secured to the riveting-block B to accomplish the same 120 result; hence I do not confine myself in any manner to the form and construction of such devices.

Having thus fully described my invention, what I claim as new, and desire to secure by 125 Letters Patent, is—

1. The combination of the pivoted stock A, riveting-block B, having a screw G, and nut C, substantially as and for the purpose set forth.

2. The combination of the stock A, riveting-block B, provided with the adjustable shoe-holder D D', the plunger P, spiral K, and 130

- spring H, having the stud I, taking in the recess I' in the screw G, substantially as and for the purpose set forth.
3. The combination of the stock A, having 5 the tongue a, the riveting-block B, having the screw G, provided with the vertical groove a' for the tongue a of the stock, and the nut C, all substantially as and for the purpose set forth.
- 10 4. In a riveting-machine, the combination of a riveting-block having a screw-threaded shank mounted in a stock, A, a nut, C, for adjusting the riveting-block, the nut being provided with vertical groove-shaped serrations 15 c, and a spring lever or stop secured to the stock, and having a projection taking in the serrations in the nut to prevent it from turning, substantially as and for the purpose set forth.
5. The combination of the vertically-adjustable riveting-block having the screw-shank G, mounted in the stock A, and the plunger P, the screw-shank G being provided with a screw, P', against which the plunger P operates, the screw P' serving to compensate for 25 the vertical adjustment of the riveting-block without changing the stroke of the plunger, substantially as and for the purpose set forth.

In testimony whereof I have hereunto signed my name, in the presence of two attesting witnesses, at Syracuse, in the county of Onondaga, in the State of New York, this 18th day of December, 1886.

JACOB J. UNBEHEND.
